(57) CLAIM

The ornamental design for bottle, as shown and described.

DESCRIPTION

FIG. 1 is a right, front perspective view of a bottle according to the present invention;

FIG. 2 is a right side elevational view of the bottle of FIG. 1;

FIG. 3 is a left side elevational view of the bottle of FIG. 1;

FIG. 4 is a front elevational view of the bottle of FIG. 1;

FIG. 5 is a rear elevational view of the bottle of FIG. 1;

FIG. 6 is a top plan view of the bottle of FIG. 1; and,

FIG. 7 is a bottom plan view of the bottle of FIG. 1.

The evenly-dashed broken lines illustrate portions of the bottle that form no part of the claim. The dot-dash broken line in FIG. 7 defines the bounds of the claim and forms no part thereof.

1 Claim, 4 Drawing Sheets
